UNITED STATES PATENT OFFICE.

JOSEPH BECVAR, OF COLLINWOOD, OHIO.

DESIGN FOR A GAS HEATING-STOVE.

No. 38,895.

Specification for Design.

Patented Nov. 19, 1907.

Application filed October 14, 1907. Serial No. 397,461. Term of patent 14 years.

To all whom it may concern:

Be it known that I, JOSEPH BECVAR, a citizen of the United States, residing at Collinwood, in the county of Cuyahoga and State of Ohio, have invented a new and original and ornamental Design for a Gas Heating-Stove, of which the following is a specification, reference being had to the accompanying drawing, forming part thereof.

The drawing is a perspective view of a

stove whose ornamentation embodies my new design.

I claim:

The ornamental design for a gas heating stove, as shown.

JOSEPH BECVAR.
